ROBERT D. PIKE, OF SAN FRANCISCO, CALIFORNIA.

ANNEALING LEER OR FURNACE.

Application filed October 25, 1922. Serial No. 596,732.

To all whom it may concern:

Be it known that I, ROBERT D. PIKE, a citizen of the United States, residing at the city and county of San Francisco and State of California, have invented new and useful Improvements in Annealing Leers or Furnaces, of which the following is a specification.

This invention relates particularly to leers of the continuously operated type in which the glass bottles or other articles are passed more or less continuously through a horizontal muffle or tunnel composed of refractory material; and during such passage are subjected to a more or less predetermined sequence of temperature to accomplish the process known as annealing. It is most usual in modern practice to impart the necessary temperature to the glass articles by causing to circulate in suitably designed flues around the outside of the muffle, hot gases of combustion. These are usually hottest near the front end of the leer where the articles enter, the same being raised as quickly as possible to the desired maximum annealing temperature and then being allowed to slowly cool during the remainder of the passage through the muffle. This method of annealing is economical because the fuel employed is relatively cheap, but only produces indifferent results in respect of uniformly removing the internal stress of the glass. This is because, in order to entirely remove these internal stresses, i. e. to perfectly anneal the glass, it is necessary to subject the glass article to a predetermined rate of heating and cooling, depending upon the nature of the article and the temperature at any given time of the annealing process or degree of passage through the muffle. These temperatures may only be allowed to vary within very narrow permissible limits, say of ± 5 deg. C. It will be obvious to anyone acquainted with the firing of gaseous or liquid fuels employed in modern leer practice that no such regulation is possible, and such being the case, perfect annealing is not possible.

It has been thought for some time that electric heating would be amenable to the desired degree of temperature control to give perfect annealing and a horizontal muffle leer has been built in which all of the heating has been accomplished by means of batteries of electrical resistances, most of which

are placed inside the muffle next to the vertical walls. In principle, this leer is the same as the fuel fired leer just described, except that the necessary heat, instead of being supplied by the combustion of fuel outside of the muffle, is supplied by passing an electric current through batteries or sets of metallic resistors, most of which are located inside the muffle. But unlike the fuel fired leer, the amount and position of the energy supplied in the electrically heated leer is subject to fine automatic control. This is accomplished by inserting a thermocouple through the center of the roof of the muffle in the locality heated by the battery of resistors which it is desired to regulate. This thermocouple comes within a few inches of the top of the glass articles. The electro-motive force of the thermocouple is used to actuate a chain of electric control apparatus of any suitable design, which controls the current passing through the battery of resistors in question so as to maintain a constant temperature of the thermocouple. In this way it has been possible to maintain the temperature of thermocouples placed about 4 feet apart within ± 5 deg. C. of a predetermined temperature.

But the current consumption of such a leer has been found to be excessive, and the annealing not yet as perfectly under control as was to be expected from the close control of the temperature of the thermocouples.

I have attached thermocouples to a bottle passing through such a leer, and have found that the actual temperature of the glass is quite different from the temperatures recorded by the thermocouples inserted through the roof to within a few inches of the glass articles. The discrepancy was most noteworthy in the receiving end of the leer where the bottles heated up more slowly than indicated by the said thermocouples and began to cool off before acquiring the maximum temperature indicated by them.

I have furthermore discovered that the cause of this discrepancy of the true temperature of the glass and the temperature of the thermocouples inserted through the roof of the muffle to within a few inches of the tops of the articles being annealed, is the relative transparency of glass to wave lengths of the visible spectrum concerned in transmitting heat energy by radiation from the electric resistors, which are at a

glowing red heat. It is desired that this heat should be efficiently transferred to the glass for heating it up to annealing temperature, but instead of such being the case, this radiant energy passes completely through the almost transparent glass and is transposed into sensible heat on the internal walls of the muffle back of the resistors and on the surface of the thermocouples. These latter, therefore, register temperatures considerably higher than the true temperatures of the glass in the heating region of the leer; and the excessive temperature of the inside face of the muffle results in high losses by radiation.

The most effective means inside the leer for transferring the heat energy from the resistors to the glass articles is the stray convection currents caused by the rising of heated air in contact with the heated resistors and inside walls of the muffle and the corresponding fall of cooler air through the glass articles, thus setting up a circulation of air which transfers heat from the resistors to the glass articles by means of convection. It is obvious that this same condition will exist whether the muffle be heated internally by electric resistors or externally by fuel. But these convection currents are stray and accidental and are not employed systematically to help accomplish the heat transfer work of the leer.

In the portion of the electrically heated leer devoted to cooling, the thermocouples do not record the true temperature of the glass which tends to cool slowly for the same reason that it heated slowly, and the result of this is that more electric current is admitted to the resistors in the cooling region than is really necessary to maintain the desired time cooling curve of the glass articles, and this current is sheer waste.

The object of my invention is to provide strong systematically effected vertical convection currents within the leer which will cause an efficient transfer of heat from the walls or resistors in the heating region to the glass articles, and from the latter to the walls in the cooling region; and these same convection currents sweeping strongly over the glass articles and thermocouples in turn, will cause the latter to register the true temperature of the glass and to control the electric input accordingly. In this way I am able to closely control the true temperature of the glass, thus causing perfect annealing and at the same time to greatly decrease the electric input to the resistors by reducing the temperature of the inside of the muffle in the heating portion and by reducing the electrical input in the cooling portion.

My invention also provides a means for combining the use of fuel and electricity whereby advantage is taken of the cheap-

ness of the former and the ease of regulation of the latter.

Referring to the drawings:

Fig. 1 is a longitudinal section through the center line of leer. 70

Fig. 2 is a side elevation.

Fig. 3 is a section on the line A—A of Fig. 1.

Fig. 4 is a section on the line B—B of Fig. 1. 75

Fig. 5 is a plan view.

Fig. 6 is a section on the line C—C of Figs. 3 and 4.

Fig. 7 shows a section of a portion of an electrically heated leer embodying my invention. 80

Fig. 8 shows a modified form of electrically heated leer provided with a fan or fans for circulating the convection currents. 85

In the drawings, 1 is a horizontally disposed tunnel or muffle, and 1' is a non-heated extension thereof which permits the glass articles to cool to atmospheric temperature before being discharged. The muffle 1 is composed of a top wall or arched roof 2 made of so called cupped tile 2' of fire clay or other suitable material, and formed with a plurality of openings 3; a side wall 4, the upper part of which is composed of cupped tile 4' and base of fire brick 4''; and a bottom wall 5 composed of cupped tile 5'. Ordinary flat shapes could be substituted for the cupped tile, but the latter are chosen because it is desired to make the walls of the muffle highly conductive to heat. 90

6 is a pan-like conveyor of any suitable design which moves slowly through the leer conveying the glass articles which are placed upon it from the receiving to the discharge end. Said conveyor is perforated with small holes to allow convection currents to pass vertically through it and it runs on guides 8 which are supported on I-beams 9, which, in turn, rest in the brick work. The conveyor passes over wheels 10 to which rotation is imparted by any suitable means. A door 11 closes the receiving end when bottles are not being put in. A baffle 12 is provided for retarding the formation of currents of air in or out. 100

Electric heating elements or resistors 13 are placed along the interior side walls of the muffle and are supported on bracket bricks 14' and 14''. These resistors are arranged in sets or batteries, and for each battery or set there is provided a thermocouple 15. These latter are connected with automatic electric control apparatus of any suitable design which so regulates the current to the several batteries or sets of resistors that the temperature reading of the thermocouple is kept practically constant at 110

the desired points for the proper annealing of the glass articles which are being conveyed through the muffle at a constant rate of travel by the pan conveyor 6.

5 The muffle 1 is backed on both sides and top by partition tiles 16 made of a refractory or semi-refractory material. These partition tiles are composed of partitions 16' and vertical passages 16''. The vertical 10 passages 16'' connect through horizontal ducts 17 with the interior of the muffle 1 at the bottom of the same and through the vertical ducts 3 with the interior of the muffle at the top center of the roof. The 15 vertical passages 16'' give a continuous connection between the ducts 3 and the ducts 17. The continuity of the tiles, themselves, is broken for purely structural reasons at the edge of the roof, and the thrust of the roof 20 arch is taken up by skew backs 18, 19, and I-beams 20 and 21 and tie rods 22.

The partition tiles, in turn, are backed up by the wall 23 composed of cup tile 23', which, as above, are used to make the wall 25 highly conducting to heat, and the said tile are composed of some suitable refractory material.

Walls 23 and 5 on the bottom of the muffle are backed by a system of flues 24. 30 These flues on the bottom are backed on the lower side by another wall 25 composed of cup tile supported on I-beams 26. The flues 24 are backed on the side and top by the fire brick wall 27 and insulating brick wall 35 28. The system of flues 24 entirely surrounds the muffle from end to end, the individual flues in said system being differentiated by the exponents "a" to "j", inclusive.

At the receiving end this flue system is 40 connected with the fire box 29, which is heated by an oil or gas burner 30 through the vertical flue 24^a. This latter conducts the heated gases to the top of the muffle and thence along the top through the opening 24^b 45 against a baffle 31, which deflects gases downwardly through the flue 24^c, thence across the bottom against a baffle 32, thence around through the flue 24^d across the bottom of the muffle outwardly, thence upward- 50 ly through the flue 24^e along the top of the muffle against a baffle 31', thence down through the flue 24^f across the bottom toward the center through the flue 24^g outwardly through the flue 24^h and upwardly 55 through the flue 24ⁱ, etc. until the gases of combustion finally pass out through the flues 33 and 33' into the stack flues 34 and thence up the stack 35.

A fan 36 is connected through a pipe 37 60 controlled by a damper 38 to the flue 24ⁱ just above the point where the latter enters into the stack flue 34. Dampers 39, 40 are arranged in the flues 33, 33' and a damper 41 is arranged in flue 24ⁱ. If it is desired to 65 have all of the gases of combustion enter

the stack flue 34 through the connecting flue 33, i. e., after they have traversed the entire flue system around the muffle, damper 39 is closed, damper 41 is opened, and damper 40 is, of course, opened. But damper 40 can 70 be closed and all of the gases of combustion can be drawn into stack flue 34 through the connecting flue 33' by opening damper 39, and if damper 41 be closed, cold air can be admitted into the flue 24ⁱ through the 75 damper 38, and this will circulate around through the flue system 24 and out through a pipe 42. Thus, the discharge portion of the muffle can be either heated by the gases of combustion or cooled by air at will, or, by 80 adjusting the necessary dampers, any desired combination of these two effects may be had.

In operation of the leer, the fuel burner in the fire box 29 and the placing of the 85 dampers 39, 40, 41, 38 are so adjusted that the temperature readings on the thermocouples 15 are slightly below the temperatures desired for perfect annealing. The fuel fired and the adjustment of dampers 90 are then kept constant. The small additional amount of temperature necessary is then supplied by electric current admitted to the resistors 13 by the automatic electric control referred to above, but not shown, 95 which also takes care of all the normal variations in operation and automatically maintains a constant reading on the thermocouples 15 with the use of a very small amount of electric current. This quantity 100 of electric current is necessarily very small because the principal heat energy required by the leer is supplied by the fuel burned in fire box 29, and only a small amount of it by the electric current, but the quantity 105 of the latter is sufficient to effect the automatic control of the temperature necessary for perfect annealing.

The combined use of the fuel and electricity, with the manifest advantage of the 110 economy of the former and the delicate adjustability of the latter, is made possible by the construction of the walls of the muffle. Heat from the resistors 13 and from the gases in flues 24 passes through the 115 highly conductive walls 2 and 4 and 23, respectively, into the partition tile 16, whence, by reason of the large surface exposed by the partitions, it is converted into sensible heat in the air in the flues 16''. On the other hand, as has been shown above, the 120 means for transferring heat from the walls of the muffle and the resistors to the glass articles is relatively inefficient because of the transparency of the latter to the radiant energy. The efficient heating of the partition tile and the inefficient heating of the glass articles results in the air in flues 16'' having a higher temperature than the air 125 surrounding the glass bottles, and this pro- 130

motes an active circulation of air up through the flues 16 down through 3, thence down through the glass articles, through the holes 7 in the pan conveyor 6 and around 5 its edges, thence over wall 5, where air begins to be heated, through flue 17 and up through the flues 16 again.

This active and systematic circulation of 10 convection currents insures that the thermocouples 15 will register the true temperature of the glass, or nearly so, because the glass, due to these currents, will tend quickly to become of the same temperature as its surroundings.

15 Another great advantage is that, as the heat flow is in opposite directions toward the center of the partition tile inwardly from the gases and outwardly from the resistors, no heat from the latter can possibly 20 escape through the outside walls of the leer and be dissipated to the atmosphere, thus eliminating a great source of loss of heat energy in electric leers as at present constructed.

25 In the cooling portion of the leer where heat is being extracted from the glass articles, the circulation of convection currents is opposite to that just described, i. e., upward through the articles and downward 30 through the flues 16".

The principle of heating as above described consists in imparting heat from both 35 sides to an enclosed air current surrounding a muffle, which heat is transferred to the articles in the interior of the muffle by convection currents induced by the temperature difference between the articles being heated (or cooled) and the surrounding air current and the flues which enclose it; and such a 40 principle of heating makes possible the simultaneous use of heating by resistors within the muffle and by hot gases of combustion from without.

45 It is obvious that many variations of the above construction may be employed without departing from the spirit of my invention. For example, the heating by gases of combustion can be omitted entirely and all the 50 heating done by the electricity, or the latter can be omitted and all heating done by the former. However, an important advantage in the way of economy resides in the combination of the two methods of heating.

55 A type of electrically heated leer is shown in Fig. 7. In this form of the device the walls are preferably constructed of fire brick A backed by hollow partition tile B, the latter having vertically extending passageways. These passageways at the bottom 60 connect with the inside of the muffle through ports C. The roof of the leer is made of standard arched brick D backed by partition tile E. The passageways in the partition tile E communicate with the 65 interior of the muffle through ports F.

The vertical partition tiles with their great exposed surface combined with the cupped fire bricks form an efficient type of "stove" for heating the air in the vertical passages from heat radiated from the elements. This air will therefore become hotter than the air surrounding the glass when the latter is being heated, because the glass is an inefficient absorber of radiant energy, and this difference of temperature 70 will cause an active circulation in the direction of the solid arrows, which in turn will promote transfer of heat to the bottles and reduce transfer to the outside through the walls.

80 When heat is to be abstracted from the glass the direction of the currents is reversed, as shown by the dotted arrows.

Another form of electrically heated leer embodying my invention is illustrated in 85 Fig. 8. In this form the roof is made straight and the inner course of cupped tile has been omitted therefrom. The side walls of the muffle include a course of cupped tile G backed by a hollow tile H. The vertical 90 passageways in the hollow tile communicate with the bottom of the muffle through ports I, and at their upper ends these passageways communicate with passageways in a course of hollow tile J, which latter are laid upon 95 T-bars K. At intervals the hollow tile J are provided with ports L opening into the interior of the muffle at the top thereof. The circulation of convection currents will be similar to that indicated in Fig. 7. 100

In this form I also show near the front end of the muffle one or more propeller fans M suspended from drive shafts N extending through the roof of the muffle on the middle line of the same. These fans are used to aid the circulation of convection currents in certain cases. As the temperature gradient between the glass articles in the leer and the walls of the muffle decreases the 110 natural circulation of the currents will decrease accordingly. In such cases the circulation may be aided by the use of these fans.

The term "muffle," as used herein, is intended to apply to a tunnel heated interiorly, as in the case of an electrically heated leer, as well as to a tunnel heated exteriorly, as in the case of a gas heated leer. 115

While the present leer or furnace is primarily intended for annealing glass articles, 120 it is capable of use for heating or annealing various other articles, as, for example, heat treating steel.

Having thus described my invention, what I claim and desire to secure by Letters Patent is:—

1. The method of transferring heat to, or abstracting heat from, glass articles in an annealing leer which consists in causing a circulation of convection currents in the 130

required direction over the glass articles in the muffle by the formation of air passageways in the interior of the walls of the muffle which are subject to direct temperature control and connecting said passageways at their opposite ends with the interior of the muffle.

2. The method of transferring heat to, or abstracting heat from, glass articles in an annealing leer which consists of forming enclosed passageways within the walls of the muffle and connecting said passageways with the interior of the muffle at the top and bottom of the latter and subjecting the walls to temperature control, whereby to cause convection currents to be circulated in the required direction over the glass articles within the muffle.

3. The method of transferring heat to, or abstracting heat from, glass articles in an annealing leer which consists in forming a lining for the side walls of the muffle with material of good thermal conductivity, arranging hollow tiles between the lining and shell of said walls, placing the passageways of the hollow tiles in communication with the interior of the muffle at the bottom and top of the latter and subjecting the lining of the side walls to temperature control whereby to cause convection currents to be circulated in the required direction over the glass articles within the muffle.

4. The method of transferring heat to, or abstracting heat from, glass articles in an annealing leer which consists in forming the muffle of the leer with side walls having vertically extending enclosed passageways, putting the passageways within the walls into communication with the interior of the muffle at the bottom of the latter, forming in the roof of the muffle enclosed passageways communicating with the passageways in the side walls and putting the passageways in the roof into communication with the interior of the muffle at the top of the latter, and subjecting said walls to temperature control to cause convection currents to be circulated in the required direction through the interior of the muffle and through the passageways within the walls and roof.

5. The method of annealing glass articles in an annealing leer which consists in forming the side walls of the muffle with vertically extending passageways in communication at their lower ends with the bottom of the muffle and opening into the top of the muffle through the roof thereof, and applying heat to opposite sides of the walls of the muffle so that air within the passageways will be raised to a higher temperature than the air surrounding the glass articles within the muffle whereby convection currents will be circulated over the

glass articles and through said passageways.

6. A method of annealing glass articles in an annealing leer which consists in forming the walls of the muffle with vertically extending passageways opening into the interior of the muffle at the bottom thereof and communicating passageways in the roof opening into the top of the muffle, arranging gas heated flues on the exterior of the walls and electrically heated means on the interior walls of the muffle whereby air within the passageways will be heated from both sides, thereby raising the temperature to a point higher than the air surrounding the glass articles within the muffle for the purpose of causing convection currents to be circulated over the glass articles and through the passageways.

7. A method of annealing glass in an annealing leer which consists in forming enclosed vertical passageways within the side walls of the muffle, connecting said passageways at the bottom with the bottom of the muffle, connecting said passageways at the top with the interior of the muffle through the roof thereof, whereby the air within the passageways will be affected by changes in the temperature of the surrounding walls, thus setting up a circulation of convection currents over the glass articles.

8. A glass annealing leer comprising a muffle, enclosed passageways formed in the walls of the muffle and communicating with the interior thereof, said passageways being so arranged as to receive heat transmitted from the walls of the muffle so as to cause convection currents to be circulated over the articles within the muffle.

9. A glass annealing leer comprising a muffle having its side walls formed with a lining of tile capable of readily conducting heat, hollow tile back of the lining having vertically extending passageways, said passageways communicating with the interior of the muffle at the bottom and with the top of the muffle through the roof thereof whereby the lining will transmit heat to the air within the passageways of the hollow tile and cause circulation of convection currents through the muffle and hollow tile.

10. A glass annealing leer comprising a muffle having its side walls formed of hollow tile with vertically extending passageways, a course of heat-conducting tile forming a lining for the walls and a course of heat-conducting tile forming a shell for the walls, the passageways in the hollow tile being in communication with the bottom and top of the muffle whereby heat will be transmitted to the air in the passageways of the partition tile, thereby causing a circulation of convection currents through the muffle and passageways.

11. A glass annealing leer comprising a

muffle having its side walls formed of hollow tile with vertically extending passageways, a course of heat-conducting tile forming a lining for the walls and a course of heat-conducting tile forming a shell for the walls, the passageways in the hollow tile being in communication with the bottom and top of the muffle, electrically controlled means for heating the lining of the muffle and fuel fired means for heating the shell of the muffle whereby heat will be imparted from both sides to air within the passageways, thus causing a circulation of convection currents through the interior of the muffle and passageways.

12. A glass annealing leer comprising a muffle having its side walls formed of hollow tile with vertically extending passageways, a lining and shell for said muffle formed of material capable of readily transmitting heat, the passageways in the hollow tile being in communication with the bottom and top of the muffle and means for heating the walls of the muffle on opposite sides of the passageways whereby to set up a circulation of convection currents through said passageways and through the interior of the muffle.

13. A glass annealing leer comprising a muffle having its side walls formed of hollow tile with vertically extending passageways, a lining and shell encasing said hollow tile, a fire box for heating the muffle, a system of flues connected with the fire box and extending in series from end to end of the muffle, said flues extending vertically on the exterior of the side walls across the top of the roof and beneath the floor of the muffle, and said passageways being in communication with the interior of the muffle at the bottom and top of the latter.

14. A glass annealing leer comprising a muffle having its side walls formed of hollow tile with vertically extending passageways, a lining and shell encasing said hollow tile, a fire box for heating the muffle, a system of flues connected with the fire box and extending in series from end to end of the muffle, said flues extending vertically on the exterior of the side walls across the top of the roof and beneath the floor of the muffle, said passageways being in communication with the interior of the muffle at the bottom and top of the latter, and means for varying the point of outlet for the heated gases passing through said flue system.

15. A method of transmitting heat to, or abstracting heat from, articles in an annealing leer which consists in causing a circulation of down or up currents over the articles in the muffle by the formation of passageways for the air in the interior of the side walls of the muffle, placing such passageways in communication with the muffle at the top and bottom, heating the interior

of the muffle and subjecting the air within the muffle to the action of a fan whereby to aid the natural circulation of the currents.

16. The method of annealing glass articles in an annealing leer which consists in forming the side walls of the muffle with enclosed vertically extending passageways, placing such passageways at one end in communication with the bottom of the muffle and at the opposite end with the top of the muffle and heating the interior of the muffle electrically, so as to set up a circulation of convection currents through said passageways and across the articles in the muffle.

17. A method of annealing glass articles in an annealing leer which consists in forming the side walls of the muffle with enclosed vertically extending passageways, placing such passageways at one end in communication with the bottom of the muffle and at the opposite end with the top of the muffle and arranging electric heating elements within the muffle upon the side walls thereof, whereby convection currents will be circulated through said passageways and across the articles in the muffle.

18. A glass annealing leer comprising a muffle having its side walls formed with enclosed vertically extending passageways connected at one end with the bottom of the muffle and at the other end with the top of the muffle, electric heating elements arranged within the muffle on the side walls thereof and thermo-couples disposed within the muffle adjacent the glass articles undergoing annealing, whereby the temperature gradient between the articles undergoing treatment and the walls of the muffle will be reduced by the circulation of convection currents.

19. A furnace for heat treating purposes comprising a muffle having its side walls formed with enclosed passageways opening into the muffle at the top and bottom and means for causing currents to be circulated through said passageways and over the articles undergoing treatment.

20. A furnace for heat treating purposes comprising a muffle having its side walls formed with enclosed passageways opening into the muffle at the top and bottom, and a fan within the muffle for circulating currents through said passageways and over the articles undergoing treatment.

21. A furnace for heat treating purposes comprising a muffle, electric heating means within the muffle, the walls of said muffle being provided with vertically extending passageways opening at one end into the bottom of the muffle and at the opposite end into the top of the muffle, said passageways being so disposed with relation to the heating elements as to cause convection currents to be circulated therethrough and over the articles undergoing treatment.

22. A furnace for heat treating purposes comprising a muffle having vertically extending passageways in its side walls opening at one end into the bottom of the muffle and at the opposite end into the top of the muffle, electric heating means within the muffle adjacent the walls which contain the

5 passageways, thermo-couples within the muffle adjacent the articles undergoing treatment and means for circulating currents through said passageways and over the articles undergoing treatment.

ROBERT D. PIKE.
